UNITED STATES PATENT OFFICE.

GEORGE S. HILL, OF STRAFFORD, NEW HAMPSHIRE, ASSIGNOR TO UNITED SHOE MACHINERY COMPANY, OF PATERSON, NEW JERSEY, A CORPORATION OF NEW JERSEY.

BUTTONHOLE-SEWING MACHINE.

1,063,795.

Specification of Letters Patent.

Patented June 3, 1913.

Application filed November 12, 1912. Serial No. 730,865.

To all whom it may concern:

Be it known that I, GEORGE S. HILL, a citizen of the United States, residing at Strafford, in the county of Strafford and State of New Hampshire, have invented certain new and useful Improvements in Buttonhole-Sewing Machines; and I do hereby declare the following to be a full, clear, and exact description of the invention, such as will enable others skilled in the art to which it appertains to make and use the same.

The invention relates to buttonhole sewing machines of that class in which a work holding clamp and stitch forming mechanism are relatively rotated in sewing about one or both ends of the buttonhole.

The object of the invention is to provide a novel and improved mechanism for effecting the relative rotation of the work clamp and sewing mechanism which will operate smoothly and in an efficient and reliable manner when the machine is run at a high rate of speed.

With this object in view the invention comprises the features of construction and combinations of parts hereinafter described and set forth in the claims.

The features of the invention will be readily understood from an inspection of the accompanying drawings and the following detailed description of the mechanism illustrated therein.

In the drawings, Figure 1 is a sectional elevation showing so much of a buttonhole sewing machine as is necessary to illustrate the application of the present invention thereto, and Figs. 2 and 3 are detail plan views showing the devices for rotating the stitch forming mechanism.

In the machine illustrated in the drawings the work is carried in a work clamp which is moved longitudinally and laterally during the sewing of a buttonhole, and the relative rotation of the work clamp and stitch forming mechanism to sew about the ends of the buttonhole, and properly position the stitches along the sides, is effected by a rotation of the stitch forming mechanism.

The work clamping devices comprise work supporting plates 1 and coöperating clamping jaws 2 which are carried by arms 3 pivotally supported upon the supporting plates. The clamping jaws are actuated by arms 4 carried by a rock shaft 5 which is in turn actuated from the cutter carrying

lever 6 through a lug 7 which engages a screw 8 carried by an arm 9 which is secured to the rock shaft. The buttonhole is cut by a cutter 10 secured on the front end of the cutter lever 6 and operated by a cam 11 which is carried by a cam gear 12 and is arranged to engage the rear end of the cutter lever. When the cutter lever is operated it closes the work clamp, and the clamp is then latched in position by latching devices indicated at 13 in Fig. 1. The latching devices are released to allow the work clamp to open when the clamp is returned to cutting position after the sewing of the buttonhole by a releasing pin 14 the upper end of which is arranged to engage a cam 15 so mounted on the frame that it may yield to allow the passage of the releasing pin during the forward movement of the work clamp.

The work clamping devices are carried upon a carrier frame 16 which is supported in suitable guides in the machine frame, and is provided near its center with a fulcrum stud 17 engaging a block 18 which is guided in a longitudinal slot 19 in the machine frame. The upper end of the fulcrum stud carries a roll engaging a cam groove in the under surface of the cam gear 12. This cam groove is shaped to give the desired longitudinal movements to the clamp carrier. Proper lateral movements are imparted to the clamp carrier during the sewing of the buttonhole by a cam groove formed in the upper surface of a gear 20, and arranged to engage a roll on one end of a lever 21. The other end of the lever 21 carries a stud 22 engaging a block 23 which slides in a longitudinal slot 24 formed in the rear end of the clamp carrier.

The stitch forming devices comprise a straight-eye-pointed upper needle 25 arranged to pass through the work at a certain distance from the edge of the buttonhole, a curved-eye-pointed under needle 26 arranged to pass through the buttonhole slit, and a coöperating looper 27. The upper needle 25 is secured to the lower end of a hollow needle bar 28 which is mounted to reciprocate through a sleeve 29 and an upper bearing 30. The needle bar is connected with the sleeve by a key and slot so that the bar will rotate with the sleeve while being free to reciprocate vertically through it. The sleeve 29 is mounted to turn in a

bearing 31, and carries a wheel 32 connected through an endless driving band 33 with a similar wheel 34 secured to the upper end of a vertical shaft 35. The band 33 is provided with lugs 36 adapted to engage holes in the wheels 32 and 34, and the band passes over an idler pulley 37 which may be adjusted to properly tension the band. The under needle and looper are carried upon a turret 38 which is mounted in bearings formed in the turret bracket 39, and is provided at its lower end with a wheel 40 similar to the wheel 32. The wheel 40 is connected through a driving band 41 with a similar wheel 42 secured to the lower end of the shaft 35. The band 41 is similar in construction to the band 33, and passes over an idle pulley 43, by which its tension may be adjusted.

During the sewing of each buttonhole the shaft 35 is turned through a complete revolution, and through the bands and wheels described, turns the stitch forming mechanism through a complete revolution. In the machine shown the rotation of the shaft 35 of the stitch forming mechanism is always in the same direction, the parts being turned rotation after rotation during the sewing of successive buttonholes. The shaft 35 and the stitch forming mechanism are thus driven from the rotary gear 20 through an arm 44, one end of which is pivotally supported upon a stud or crank pin 45 secured in the under side of the gear, and the other end of which is provided with a slot 46 extending radially from the axis of the pivot. An arm 47 is secured to the shaft 35, and is connected with the arm 44 by a stud 48 carrying a pivot block 49 which has a sliding fit in the slot 46 and is free to turn on the stud. The arm 44 carries a roll 50 which travels in a cam groove 51 formed in a disk 52 which is secured in a fixed bracket. The roll 50 is arranged to the rear of the stud 45 which carries the arm 44, so that the roll is drawn along the cam groove by the rotary travel of the stud.

During the operation of the stitch forming mechanism the driving gear 20 is rotated through a single revolution and at a uniform speed. The arms 44 and 47 and the sliding connections between the arms serve to positively and continuously connect the gear and the shaft 35, and the stationary cam groove 51 is so proportioned and arranged that the stitch forming mechanism is held stationary or moved at varying speeds during the sewing about the buttonhole, according to the part of the buttonhole at which the stitch forming mechanism is operated.

In the machine illustrated the mechanisms are so timed and arranged that the first stitch in the buttonhole is formed at the end of the buttonhole slit, and the last

stitch is completed in the same needle hole in which the first stitch was taken.

The position of the parts when the machine is started and stopped is indicated in Fig. 2. At the beginning of the sewing the cam roll 50 moves in a part 53 of the cam groove, which is so shaped that no rotary movement is imparted to the stitch forming mechanism. After the first stitch has been formed the roll travels in a part of the cam groove which accelerates the movement transmitted to the stitch forming mechanism from the uniformly rotated driving gear 20, so that the stitch forming mechanism is turned at a comparatively rapid rate during the formation of the stitches across the lower end and in passing from the end to the side of the buttonhole. The rotation of the stitch forming mechanism is then retarded so that there is comparatively little if any turning of the stitch forming mechanism in sewing along the straight side of the buttonhole, is accelerated so that the sewing mechanism is turned at a comparatively rapid rate in sewing about the eye of the buttonhole, is again retarded in sewing along the opposite straight side of the buttonhole, and is again accelerated in passing from the side to the end and sewing across the end of the buttonhole. As the sewing is completed the cam roll travels in the part 53 of the cam groove so that no rotary movement is imparted to the stitch forming mechanism during the last retracting movement of the needle, and the stitch forming mechanism is therefore stopped in proper position to begin the sewing of the next buttonhole.

By the mechanism described the rotation of the stitch forming mechanism is positively and uniformly controlled while the actuating mechanism is operating at a high rate of speed, and the construction and arrangement of the connections between the driving gear and shaft 35 enable the use of a cam groove having easy curves for controlling the movements of the arm 44 without undue wear or friction.

The main cam gear and the driving gear 20 are both driven through a single revolution during the sewing of each buttonhole, and the driving mechanism for the gears is so constructed and operated that the gear 20 rotates only during the sewing of the buttonhole, while the gear 12 is driven independently at the beginning and at the end of the cycle of operations performed by the machine to actuate the cutter and to move the work from cutting to sewing position before the sewing begins, and from sewing back to cutting position after the sewing of the buttonhole is completed.

While the invention has been illustrated and described as embodied in a machine in which the relative rotation between the

- work clamp and stitch forming mechanism is effected by rotation of the stitch forming mechanism, and in which the stitch forming mechanism is rotated rotation after rotation 5 in the same direction in sewing about successive buttonholes, it will be understood that the invention is not limited in its application to a machine in which the relative rotation is thus effected, or in which there 10 is no reverse rotation of the stitch forming mechanism, but may be embodied with advantage in other constructions.
- Having explained the nature and object of the invention, and specifically described 15 one form of machine in which it may be embodied, what is claimed is:—
1. A buttonhole sewing machine, having, in combination, stitch forming and work holding mechanisms, mechanism for relatively 20 rotating the work holding and stitch forming mechanisms to sew about a buttonhole comprising a rotary driving member, an arm pivoted to the driving member, a driven shaft provided with an arm, a sliding connection between the arms, and a cam 25 acting on the pivoted arm to vary the motion transmitted to the shaft.
  2. A buttonhole sewing machine, having, in combination, stitch forming and work holding mechanisms, mechanism for relatively 30 rotating the work holding the stitch forming mechanisms to sew about a buttonhole comprising a driven shaft, a rotary driving member, an arm secured to the 35 shaft, an arm pivoted to the driving member, a radial slot in one of the arms, a stud on the other arm engaging the slot, and a cam 40 acting on the pivoted arm to vary the motion transmitted to the shaft.
  3. A buttonhole sewing machine, having,

in combination, stitch forming and work holding mechanisms, mechanism for relatively rotating the work holding and stitch forming mechanisms to sew about a buttonhole comprising a driven shaft, an arm secured to the shaft, a concentric rotary driving member, an arm pivoted to the driving member, a radial slot in the pivoted arm, a stud on the other arm carrying a pivot block sliding in the slot, a roll carried by the pivoted arm, and a stationary cam along which the roll travels for varying the motion transmitted through the connected arms. 45

4. A buttonhole sewing machine, having, 50 in combination, upper and under thread handling mechanism, rotary supports for said mechanism, a shaft connected to rotate the supports, a rotating driving member, an arm pivoted on the driving member, an 55 arm secured to the shaft, a sliding connection between the arms, and a cam acting on the pivoted arm for varying the motion transmitted to the supports.

5. A buttonhole sewing machine, having, 60 in combination, stitch forming and work holding mechanisms, mechanism for relatively 65 rotating the work holding and stitch forming mechanisms to sew about a buttonhole comprising a shaft, an arm secured to the 70 shaft, a rotary driver, an arm pivoted to the driver, a sliding connection between the arms, a roll on the pivoted arm arranged at the rear of the pivot, and a stationary cam along which the roll travels for varying the 75 motion transmitted to the shaft.
